UNITED STATES PATENT OFFICE.

MARGARET ANNE SINCLAIR, OF DEVONPORT, AUCKLAND, NEW ZEALAND.

GAME.

Application filed September 27, 1919. Serial No. 326,704.

To all whom it may concern:

Be it known that I, MARGARET A. SINCLAIR, a subject to the King of Great Britain, residing at Devonport, Auckland, New Zealand, have invented new and useful Improvements in Games, of which the following is a specification.

This invention relates to a new card game which may be played by persons not familiar with the ordinary playing cards and in which the procedure of play is simple and one which may be followed by children as well as adults.

The game consists of providing a number of sets of cards made of a suitable and handy size. Each set has a name, comprising a word or words, given, which serves to denote its particular set. The No. 1 card has its name shown centrally on its face and on the succeeding cards of the set the name appears in one of the corners of each card, while a word or words or an expression in words having some reference to the name of the set is shown centrally on the face of one card of the set. Each succeeding card of the set has its own word or words or expression of words shown centrally on its face and the name of the set on one of its corners. All the centrally placed word or words or expression of words on the succeeding cards must have some reference to the name of the set. Arrows are shown on the face of each card, the number of which vary on all the cards of the set. The number of cards also vary in the different sets, some having only one while others have six or more.

The drawings illustrate a single set or suit and in which,

Figure 1 shows the major or No. 1 card of the set; and

Figures 2, 3, 4 and 5 illustrate the minor cards thereof.

As shown in Figure 1, the major card carries the word or words designating the name of the set and also a representation of said word or words. The set shown comprises a representation of cupid and this set would be known as the cupid set. Each card of the set has the word "Cupid" centrally arranged on the card. The other cards of the set are respectively marked "Royal archer," "Quiver," "Bow" and "Arrows." As before stated, each card has the word "Cupid" in one corner, and a numeral representing the number of the card in the

set, in another corner. The cards are all marked with arrows, as shown. The game may consist of any number of sets or suits and the numbers of cards in the different sets or suits may vary, but each set must contain a major card bearing the name of the set and minor cards bearing names having reference to the name of the set and also the name of the set in one corner. For instance, the other sets may be composed of cards designated as follows:

"Venus" Minor. Doves. Roses. (4)
"Maud" Garden. My own. (3)
"Rustic" Huldah. Window. Apples. (4)
"Factory" Lad. Lass. Shawl. Factory gate. (5)
"Admiral" Ship. Child. Nurse. (4)
"Lieutenant" Fort. Motor. Accident. (4)
"Sailor" Nancy Lee. Boat ahoy. She bumps. (4)

"Garden Gate" Never protected season. Never too early. Never too late. (4)

"Bower" Princess. Maid of honor. Lady in waiting (4)

"Mary" Stile. Field. Side by side. (4)

"Knight" Lady. Castle. Page. (4)

"The old old story" Say when. A shaft at random sent finds mark. (4) Total 53.

In playing the cards any number of players can sit round the table, and after the cards are shuffled they are dealt out to the players face down. The cards are placed in order of sets and the first player must lead with the Number 1. card of any set that he may have in his hand. The player who leads off is chosen by the turn of a coin or as may be otherwise decided, and he leads off with a Number 1. card of any set he may have in his hand, but should he not have a Number 1 card in his hand the right to lead passes to the next in succession who may have a Number 1. card, and then each succeeding player must follow suit by playing a card of the same set as led and if he has no card of that set he must pay a counter into the pool, and the next player plays, unless he also has no card of the set, when he in turn, pays a counter, and so the play or game proceeds. When the set that leads is exhausted then a Number 1 card of another set is dealt in the same manner, and so the game continues until all the cards are played.

The game is won by the greatest number of arrows appearing on the cards of the tricks taken by the respective players.

By preference the game will be known as the "Royal archer" card game.

The game may also be played as what may be referred to as "blind fold" as follows:—Any number up to 13 can play. To decide who shall lead.—A player deals the cards round face up, and the first dealt a Number 1 card of any set becomes the dealer. The cards are then shuffled and cut, and 10 dealt out to the players face down. Players must not look at their cards. The dealer plays the first card in his hand face down, the next player on his left follows with another card face down, till four 15 cards have been played, one by one each player, the fourth player taking the trick. Always face down. The next player again plays the top card of his hand face down, other three players following in order, the 20 fourth each time taking the trick until the cards are played out. When the cards are reversed the game is won by the player holding the highest number of arrows.

The game may also be played as follows:—Any number up to 13 can play. To decide who shall lead:—A player deals the cards round and face up and the first dealt a No. 1 card of any set becomes the dealer. The cards are then shuffled and cut, and 30 dealt out to the players face down as in bridge. The dealer must lead a No. 1 card of any set he may have, but failing to have one, the lead passes to the next in succession who

has a No. 1 card. The next player must follow with No. 2 of the same set, and failing pays a counter into the pool, this forfeiture continues until that set is worked out in numerical order. The player who plays the highest numbered card of the set taking the trick. The next player follows 40 with No. 1 card of any other set, (or a forfeit) and the game continues until the 13 sets are played out. The winners of tricks then count the number of arrows on their cards and the highest number wins the stakes. No player may play more than one card at a time, although he holds a sequence of the set, as this would reduce the forfeits. 45

What I claim is:—

A deck of cards comprised of thirteen 50 suits, a major card in each suit provided with the name of the suit in each left hand corner and center respectively and the numeral in each right hand corner, a plurality 55 of minor cards in each suit and each minor card having the name of its suit in each left hand corner, a name in the center having reference to the name of the suit in which it belongs and a numeral greater than the numeral 1 in the right hand corner, the number of cards in each suit varying in number from three to five and making a total of fifty-three cards to be played as described. 60

In testimony whereof I affix my signature.

MARGARET ANNE SINCLAIR.
